UNITED STATES PATENT OFFICE.

DAVID J. CONDON, OF KENWOOD PARK, IOWA.

EMERGENCY VAULT AND SAFE LOCK.

1,398,628.

Specification of Letters Patent.

Patented Nov. 29, 1921.

Application filed January 17, 1921. Serial No. 437,804.

To all whom it may concern:

Be it known that I, DAVID J. CONDON, a citizen of the United States, residing at Kenwood Park, in the county of Linn and State of Iowa, have invented certain new and useful Improvements in Emergency Vault and Safe Locks, of which the following is a specification, reference being had therein to the accompanying drawings.

10 This invention relates to certain new and useful improvements in emergency vault and safe locks, the object being to provide the door of the safe or vault with an auxiliary locking mechanism normally held out of engagement with the bolt-work in such a manner as to be automatically released when the primary lock is tampered with so as to lock the bolt-work of the safe or vault when the primary lock is tampered with in any way.

15 A further object of the invention is to provide an emergency vault and safe lock which is so constructed that the same can be readily attached to the door of any of the well known makes of vaults and safes without drilling the safe door in any way, the auxiliary locking mechanism consisting of a pair of locking arms pivotally mounted upon a suitable support and geared together so as to cause the same to work in unison and adapted to engage the bolt-work when released in order to prevent the bolt-work from being operated if the primary lock should be removed or tampered with in any way.

20 Another and further object of the invention is to provide novel means for holding the locking arms in raised position out of the path of movement of the bolt-work so that the bolt-work of the safe or vault door can be operated in the ordinary manner without danger of releasing the locking arms and lock the bolt-work accidentally.

25 Another and further object of the invention is to provide novel means for locking the arms in horizontal position when released in order to prevent the arms from being moved upwardly by a "yegg" if the primary lock should be burnt off.

30 Other and further objects and advantages of the invention will be hereinafter set forth and the novel features thereof defined by the appended claims.

With these objects in view,

Figure 1 is a rear elevation of a safe or vault door showing the application of my improved construction of emergency lock in

raised position ready to be dropped if the primary lock is tampered with;

Fig. 2 is a detail elevation, partly in section, showing the emergency lock in locked position;

Fig. 3 is a perspective view of the support detached;

Fig. 4 is a perspective view of one of the locking arms and weight carried thereby;

Fig. 5 is a perspective view of a slightly modified form of support;

Fig. 6 is an elevation of a form of support adapted to be used on a vault door construction in which the central bar is omitted showing the support mounted on one of the bolts;

Fig. 7 is a section taken on line 7—7 of Fig. 6;

Fig. 8 is a detail perspective view of a slightly modified form of bridge member for the primary lock; and

Fig. 9 is a detail perspective view showing means for supporting the locking arms when arranged below the bridge member of the primary lock.

In the drawing 1 indicates the door-case of the safe or vault, 2 the vault or safe door which is herein shown provided with a marginal flange 3 having openings 4 to receive the horizontally disposed locking bolts 5 which are connected together adjacent their ends by tie bars 6 so as to cause the bolts to work in unison. A central vertically disposed bar 7 is arranged between the frame provided with openings through which the bolts 5 pass which constitutes the ordinary construction of vault or safe door now in use.

The door is provided with the usual combination lock 8 and bolt-shifter 9 by means of which the bolts 5 are moved back and forth in order to lock and unlock the door in the usual manner and the particular construction of combination lock and bolt-shifter employed forms no part of my invention, as my improved construction of emergency lock is capable of being used in connection with all of the well known makes of combination locks now in use on safe and vault doors. The above description is given so that the operation of my improved construction of emergency lock can be readily understood when applied to a vault or safe door.

My improved construction of emergency lock comprises a support 10 in the form of a

channel member adapted to embrace the centrally disposed bar 7 of the door and be secured in position by set screws 11, said support being provided with a reduced portion 12 having threaded openings 13 in which are arranged stud bolts 14 on which are pivotally mounted the enlarged end portions 15 and 16 of locking arms 17 and 18, said arms being offset as shown at 19 and 20 and 10 provided with adjustably mounted weights 21 and 22 adjacent their ends, the free ends of said arms being adapted to engage the tie bars 6 when dropped into horizontal position so as to lock the bolt-shifter as will be hereinafter fully described.

The enlarged portions 15 and 16 of the arms 17 and 18 are provided with meshing teeth 23 and 24 in order to cause the bars to work in unison, the locking bar 18 being 20 provided with a lip 25 which is engaged by the bottom portion 26 of the enlarged portion 15 of the arm 17 in order to hold the arms in horizontal position and to limit the downward movement of the arms.

25 The offset portions 19 and 20 of the arms are adapted to engage the shoulders 27 formed by the reduced portion 12 of the support in order to limit the upward movement of the arms.

30 Extending across the combination lock and bolt-shifter is a bridge member 28 herein shown in the form of a wire having one of its ends connected to the combination lock and the other end to the marginal frame 3, 35 said bridge member being formed of such a material that if the combination lock is burnt by an oxy-acetylene torch, the same will fuse or if the combination lock is blown off bodily, the bridge member will be removed from a horizontal position so as to 40 allow the emergency lock to be set into operation as will be hereinafter fully described.

In order to hold the arms in raised position as shown in Fig. 1, I provide the arm 45 18 with a socket 29 into which extends the upper end of a steel rod 30, the lower end being provided with a compound bend 31, the hook portion formed thereby being adapted to embrace the bridge member 28 50 and hold the arms in raised position out of the path of travel of the tie bars of the bolt-shifter.

Pivotaly mounted on a stud 32 secured to the support 10 is a pivoted gravity dog 33 55 which is adapted to engage a projection 34 formed on the arm 17 when the locking arms are dropped into horizontal position so as to lock the arms in this position and prevent the same from being raised by the "yegg" 60 through the medium of instruments inserted through the hole formed in the safe or vault door by the removal of the primary combination lock or in any other way.

When the emergency lock is installed on a 65 vault or safe door, a screw 35 is placed on

the inner side of the door at a certain point by measurements which are made of record and to this screw wires 36 and 37 are fastened which have their free ends connected respectively to the weight 21 of the arm 17 70 and the gravity locking dog 33 so that after the emergency lock has been set by the tampering with of the main or primary lock, a suitable opening can be bored through the safe door and the wires grasped in order 75 to raise the arms and gravity dog in order to release the emergency lock and allow the door to be opened.

In use the inner face of the door is enclosed by a suitable covering A or a calendar 80 is hung on the inner face of the door so as to cover the emergency lock so that no one would be aware of its existence when the safe or vault door is left open.

In the modification shown in Fig. 5 the 85 support 38 is constructed to be used on a vault door having a narrow central bar and is adapted to carry the usual locking arms and pivoted dog.

In Fig. 6 I have shown a support 39 especially adapted to be used on a vault door constructed without a centrally disposed bar, the support having a socket 40 to receive one of the bolts 5 of the door for suspending the same thereon, said support being secured in position upon the bolt by a set screw 41. In this construction the lower end of the support 39 is provided with threaded bosses 42 to receive studs on which the pivoted arms are mounted and the support carries a locking dog for engaging one of the arms.

In Fig. 8 I have shown a modified form of bridge member comprising a bar 43 having a serrated portion 44 to receive the compound bend portion 31 of the support 30 so that the position of the support 30 can be adjusted in order to adjust the arms and support the same in any desired position.

In the modification shown in Fig. 9 I show 110 means for supporting the arms from above by a support 45 which is provided with a compound bend portion 46 adapted to be seated on the bridge member 47, the lower end of the support 45 being provided with a 115 hook portion 48 adapted to extend into a socket 49 formed in one of the locking arms 50 and it will be seen that by this construction that when the bridge member is displaced the locking arms will be released so 120 that they will drop by gravity and lock the bolt-work of the safe or vault door.

The operation of the emergency lock as herein shown is as follows: Assuming that the emergency lock is in the position shown 125 in Fig. 1 with the bridge member spanning the combination and bolt-shifter of the safe or vault door, if the combination lock is tampered with or excessive heat applied to the same, the bridge member will either fuse or 130

- be removed bodily from over the combination lock, which releases the support which drops by gravity from under the locking arms. When the locking arms drop, which 5 are accelerated by the weights carried thereby, the free ends engage the tie bars of the bolts so that the bolts cannot be moved. As the locking arms drop by gravity, the gravity dog falls by gravity into engagement 10 with the projection on one of the arms and locks the same so as to prevent the arms from being moved upwardly until the dog is moved out of engagement with the projection of the arm.
- 15 As the support is moved from under the locking arm provided with a socket, this arm moves downwardly by gravity and as the teeth carried thereby are enmeshed with the teeth of the companion arm, the two 20 arms move in unison until the lip of the arm engages the shoulder formed by the other arm which limits the downward movement so as to hold the arms in the horizontal position shown in Fig. 2.
- 25 After the emergency lock has been released by some unscrupulous person tampering with the primary lock of the safe or vault door, in order to release the emergency lock it is only necessary to bore a hole through 30 the vault door at a point determined by the measurements previously taken and pull upwardly on the wires which will raise the locking arms out of engagement with the tie bars of the bolts.
- 35 From the foregoing description it will be seen that I have provided an emergency lock so constructed that it can be applied to any of the well known makes of vaults or safe doors now in use and composed of a 40 pair of locking arms geared together and held in raised position by a movable support mounted upon a separable member spanning the primary lock of the vault or safe door in such a manner that the arms 45 will be released so as to form a positive lock for the safe or vault door when the primary lock is tampered with.
- What I claim is:—
1. The combination with a safe and the 50 door therefor having locking mechanism including a combination lock and bolt work, of a pair of gravity locking arms carried by the door, a bridge member spanning said locking mechanism, a support for holding 55 said locking arms mounted upon said bridge member and means for locking said arms in horizontal position against the bolt-work when released by said support.
  2. The combination with a safe having a 60 door provided with locking mechanism including a combination lock and bolt-work, of a support carried by said door, pivoted arms mounted upon said support provided with meshing gears, means for limiting the 65 downward movement of said locking arms,
  3. The combination with a safe having a 70 door provided with locking mechanism including a combination lock and bolt-work, of a support carried by said door, pivoted arms mounted upon said support provided with meshing gears, means for limiting the 75 downward movement of said locking arms, a bridge member spanning the combination lock of said door, a supporting member mounted upon said bridge member engaging one of said arms for holding said arms in raised position, a pivoted gravity dog carried by said support engaging one of said arms for holding said arms with the ends against said bolt-work when released by said supporting member.
  4. An auxiliary locking mechanism for safe doors comprising a support adapted to be carried by the door, said support being 80 provided with stud bolts, of a pair of arms pivotally mounted upon said stud bolts provided with meshing teeth for causing said arms to move in unison, means for limiting the downward movement of said arms, a gravity locking dog carried by said support adapted to engage the projection on one of said arms for holding said arms in horizontal position, and separable means for holding said arms in raised position.
  5. The combination with a safe door having a main locking mechanism including a combination lock and bolt-work therefor, of a support having means for fastening the 110 same to the door, said support being provided with stud bolts, of a pair of weighted arms pivotally mounted upon said stud bolts provided with meshing gears, one of said arms being provided with a projection, said 115 arms being arranged to engage the bolt-work of said door when in horizontal position, a gravity locking dog carried by said support adapted to engage the projection of said arm when said arms are moved into horizontal position, a bridge member spanning said combination lock and a support detachably mounted upon said bridge member having its free end in engagement with one of said arms for holding said arms in 120 raised position.
- In testimony whereof I hereunto affix my signature.

DAVID J. CONDON.
